poration of Pennsylvania

Application June 29, 1933, Serial No. 48,593

Term of patent 14 years

To all whom it may concern:

Be it known that I, GUSTAV GASTRICH, a citizen of the United States of America, residing at Wyomissing, in the county of Berks and State of Pennsylvania have invented a new, original and ornamental Design for a Knitted Fabric, of which the following is a specification, reference being had to the accompanying drawing, forming part thereof.

The figure is a plan view of a knitted fabric, showing my new design, the obverse side of the fabric being the same.

In the view the fabric is shown enlarged approximately one and one-half times actual size, but which in the reduction to patent size will show the fabric approximately actual size.

I claim:

The ornamental design for a knitted fabric as shown and described.

In testimony whereof I affix my signature.

GUSTAV GASTRICH.
